US00D880490S

(12) **United States Design Patent** (10) Patent No.: **US D880,490 S**
Jensen et al. (45) Date of Patent: ** Apr. 7, 2020

- (54) **DISPLAY SCREEN OR PORTION THEREOF WITH A GRAPHICAL USER INTERFACE**

(71) Applicant: **Domo, Inc.**, American Fork, UT (US)

(72) Inventors: **Gavin Jensen**, Lehi, UT (US); **Aryel Cianflone**, Salt Lake City, UT (US); **Matt Belkin**, Salt Lake City, UT (US); **Sam Thomas**, Lehi, UT (US)

(73) Assignee: **Domo, Inc.**, American Fork, UT (US)

(**) Term: **15 Years**

(21) Appl. No.: 29/621,265

(22) Filed: Oct. 5, 2017

Related U.S. Application Data

- (63) Continuation of application No. 29/523,007, filed on Apr. 6, 2015, now abandoned.

CLAIM

The ornamental design for a display screen or portion thereof with a graphical user interface, as shown and described.

DESCRIPTION

The FIGURE is a front view of a display screen or portion thereof with a graphical user interface showing the new design.

The outermost broken lines illustrate the display screen or portions thereof. The remaining broken lines illustrate portions of the graphical user interface. None of the broken lines form part of the claimed design.
